Attorney

UNITED STATES PATENT OFFICE.

PAUL H. QUICK, OF GLOVERSVILLE, NEW YORK, ASSIGNOR TO KINGSBORO SILK MILLS, INC., OF GLOVERSVILLE, NEW YORK.

WARP KNIT FABRIC AND METHOD OF MAKING THE SAME.

Application filed December 26, 1922. Serial No. 609,093.

To all whom it may concern:

Be it known that I, PAUL H. QUICK, a citizen of the United States, residing at Gloversville, in the county of Fulton and State of New York, have invented new and useful Improvements in Warp Knit Fabrics and Methods of Making the Same, of which the following is a specification.

This invention relates to a new and improved warp knit fabric, and to a method of making the same, and particularly to improvements in and relating to the manufacture of jersey knit silk fabric of the kind commonly known in the trade as "glove silk," which as ordinarily made consists of two sets of silk threads knit looped and lapped upon the needles of a two-beam, two guide-bar "Tricot" or fast warp knitting machine.

This "glove silk" fabric, among its other uses, is employed in the manufacture of cut silk hosiery, and is a very satisfactory material for making the leg portions of thin silk hosiery. It is not, however, satisfactory for use in making the foot and heel portions of hosiery, as it lacks the necessary thickness, strength and durability to give good service and long wear. For this reason hosiery made entirely of glove silk fabric, while desirable because of its comfortable feel to the foot and fine appearance on the leg, does not possess the long wearing qualities of silk hosiery having foot and heel portions made of some thicker, stronger and more durable material.

One object of my invention is to provide an improved glove silk fabric of materially increased thickness, strength and durability, and which is highly suitable for satisfactory use in making the foot and heel portions of hosiery and for other general purposes where the use of an even surfaced cloth of heavy texture is desired.

Another object of the invention is to provide a knit silk fabric which is made of silk threads strengthened by the addition of threads of a stronger material, but which, upon its face, will have the appearance of being made wholly of silk, and which is not limited to the use above stated, but is also suitable for use for many other purposes where a silk effect is desired coupled with long wear, as in the manufacture of corsets, brassières, underwear, men's soft collars, shirts, etc.

Still another object of the invention is

to provide a fabric of the character described which, while knitted, will have the appearance of a woven fabric.

Still another object of the invention is to provide a method of making such a fabric, whereby the same may be made on a Tricot or fast warp knitting machine.

In the drawing,—

Figure 1 is a view of parts of a knitting machine involved in carrying out my process and showing the arrangement for the action of the knitting mechanism on the threads.

Figure 2 is a view of a portion of fabric made in accordance with my invention, the loops being spread and exaggerated in size to show the mode of arrangement and relation thereof.

Referring now more particularly to Figure 1 of the drawing, 1 and 2 represent the usual beams or spools of a "Tricot" or fast warp knitting machine, from which pass the front and rear threads 3 and 4 commonly employed in the production of jersey knit fabrics. These threads extend from the beams 1 and 2 over spring tension bars 5 and 6 to and through the eyes 7 and 8 of guide bars 9 and 10. 11 is the usual presser bar, 12 the barbed needle, 13 the needle bar, and 14 the needle bar guide or sinker. In the ordinary operation of a "Tricot" or fast warp knitting machine threads 3 and 4 only are employed, which are linked or looped and lapped upon the needles and manipulated by the cooperating parts of the machine to produce an elastic knitted fabric which is uniform in weight, thickness and appearance throughout. For the production of my new fabric, however, I supply the machine with an added or third beam 15 and tension bar 16, and also a third guide bar 17 provided with a guide eye 18, such added parts being employed for the introduction, in a novel manner, of a third thread 19 which extends from the beam 15 over the bar 16 and through the guide eye for introduction with the threads 3 and 4 into the fabric in the manner hereinafter specified. At 20 is shown the completed knitted fabric which winds upon the cloth roll 21.

In the method of making my improved fabric, the threads 3, 4 and 19 are constantly supplied from the beams 1, 2 and 15 to the knitting mechanism and the threads 3 and 4 are knitted together so as to form an upper and a lower warp and the warp threads 19

laid therebetween and interlaced therewith as an intermediate warp so as to produce a fabric which is of increased thickness, strength and weight smooth and even surfaced and of uniform thickness, strength and weight throughout. Furthermore, the said threads 3, 4 and 19 are so associated as to form a fabric having certain novel characteristic features from the standpoint of 10 structure and appearance adapting it particularly for the purposes for which it is designed, as will hereinafter more fully appear.

By reference to Figure 1 it will be seen 15 that the threads 3 and 4 feed from the beams 1 and 2 through the eyes 7 and 8 of the guide bars 9 and 10, which guide bars move from right to left, in opposite directions, and lap or loop the threads on the 20 needles in the usual way for making jersey fabrics. In producing a silk faced fabric in accordance with my invention the threads 3 and 4 are silk threads, which, for convenience of description, may be termed front 25 and rear silk threads, while the threads 19, which, for convenience of description, may be termed backing threads, may be of cotton, linen or wool, or any material suitable for giving increased strength and durability 30 to the knitted silk fabric. The thread loops 4 are arranged or spaced in adjacent single rows or wales and have a single needle traverse between successive needles in the knitting action, while the thread loops 3 are arranged two rows or wales apart, measured 35 with relation to the rows of threads 4, and have a two needle traverse between alternately arranged needles in the knitting action, in which they jump from one needle to 40 another across an intervening needle. The distance traversed by the threads 3 accordingly in the formation of its threads loops requires a greater amount of silk feed (about one third more) than that required 45 by the threads 4. The threads 3 in the knit are thrown over toward the front and form the major portion of the face surface of the fabric, the remainder of which is completed by the threads 4, and this excess of silk on 50 the face side of the fabric covers and conceals all portions of the threads 19 at the front, thus giving at the front of the fabric the appearance of a fabric made entirely of silk throughout. In introducing the back- 55 ing thread 19 the guide 17 on its descent carries the thread down against the back of the needle, between the portions of the threads 3 and 4 at such side of the needle, said thread 19 thence extending across or 60 lapping the needle and passing to the front thereof and finally between the threads 3 and 4 at the point where the thread loops are closed to form the completed fabric 20. In this operation the thread 19 has a two 65 needle traverse like the thread 3 so that said

thread 19 will give an excess of material proportionate to that of threads 4, and similar to that of threads 3, for the formation of the major portion of the back of the fabric, which is completed by portions of 70 threads 4.

In so introducing the backing thread 19 it will be observed, by reference to Figure 2, that the threads 19 are not linked or looped and knitted in with the threads 3 and 4, but 75 are laid in between the threads 3 and 4, passing zig-zag fashion back and forth between alternate rows of the loops of threads 80 3 and 4 and across an intermediate row of said thread loops. Also that at the points of intersection or bends of the zig-zag thread stretches 19, the threads 19 pass through the loops of threads 3 and 4 and are thereby bound and held in position in the 85 fabric. The arrangement described throws the binder threads 19 over at the rear of the silk threads 3 and 4 so that the threads 19 form the major portion of the rear surface of the fabric, the remainder of said 90 surface being made up by portions of the threads 4. In other words, by this method I inlay a third warp 19 complete between an upper warp 3 and a lower warp 4 by a regular traverse of said warp 19 around two 95 needles, while the upper and lower warps are knitted to form a regular tricot fabric over such third or intermediate warp. In the completed fabric, therefore, the silk threads 3, in entirety, and the major portions 100 of the silk threads 4 form the front surface of the fabric, which is entirely of silk, while the backing threads 19, in entirety, and minor portions of the threads 4, form the rear surface of the fabric which is composed almost entirely of the thread material of greater strength and durability. As an example of the composition of the 105 back of the fabric it may be assumed that the threads 4 and 19 are of different and contrasting colors, in which event the predominating color of the back of the fabric will be that of the threads 19, flecked by the color of the portions of the threads 4 which show at the rear.

A fabric thus made will have all the appearance at the front of being made entirely of silk, while it will be thickened, strengthened and rendered of greatly increased durability by the backing threads, which, by reason of their being thrown entirely to the rear, will serve their stated function without detracting from the effect and appearance to be given to the face of the fabric. When used as foot and heel portions in the manufacture of cut-silk stockings, whose body portions are made of thin jersey silk, my improved fabric will furnish thick, strong and durable foot and heel portions having the appearance of being made of the same material as the stocking body and 115 120 125 130

which, if desired, may be of a color or pattern to accord therewith. By reason also of the fact that a quite heavy appearance of silk is presented at the front, a semblance 5 of heavy silk goods is furnished, and, as the threads 19 extend throughout the fabric, which is of uniform weight, thickness and strength, a substitute for elastic all-silk material is provided which is suitable for use 10 for many purposes, as in the manufacture of gloves, corsets, brassières, underwear, men's soft collars, shirts, and for all purposes where an all-silk effect is desired coupled with long wearing qualities. A valuable 15 feature of the product, constructed and made according to the method described, is that while the fabric is a knit fabric, it has every appearance in texture of being a fine quality woven fabric, whereby its 20 qualifications for many and various uses is increased. This fabric will also stand stretching (finishing) and preserve its shape better than ordinary jersey knit goods.

Having thus fully described my invention, 25 I claim:

1. The herein-described warp fabric consisting of two sets of looped silk threads respectively of single traverse and of double traverse, and a third set of threads of greater 30 strength and durability than said silk threads, the silk threads being arranged to form upper and lower warps and the third threads intermediate warps laid between said upper and lower warps, said intermediate 35 warp threads being inlaid in double traverse arrangement between the upper and lower warps and held by one set of the silk warps, the silk warps being knitted to produce a regular tricot fabric over the 40 intermediate warps.
  2. The herein-described warp fabric comprising a jersey knit fabric structure made up of two sets of looped silk body threads, respectively of single traverse and of double 45 traverse, the material of the double traverse body threads being in excess of the material of the single traverse body threads and arranged to mainly form the face of the fabric, and a backing thread of a material of
- greater strength and durability than the 50 body threads inlaid in double traverse arrangement between two needles back and forth between the body threads throughout the length and breadth of the fabric and held by said single traverse body threads, 55 said backing threads being arranged to mainly form the back of the fabric, whereby a fabric is produced which is of greater weight, thickness and strength than the jersey knit body and of substantially uniform weight, strength and thickness throughout, said fabric being smooth surfaced on both sides and presenting a solid silk fabric appearance at the front thereof and a reinforcing surface mainly constituted by 60 the backing threads at the rear thereof.
3. The method of producing a jersey knit warp fabric of increased weight, strength and thickness, which consists in supplying from two warp beams and two coacting 70 guides two silk body threads to certain needles, looping together said threads by the action of the needles and associated parts of the knitting mechanism while causing one body thread to have a back and forth 75 single traverse and the other body thread to have a back and forth double traverse, thereby forming a plain jersey knit fabric structure of which the double traverse silk threads mainly form the front having added 80 silk material in excess of the silk material contained by the single traverse silk threads, supplying from a third beam and a coacting third guide a backing thread of greater strength and durability than the silk threads 85 and lapping said backing threads via a back and forth zig-zag double traverse around two needles without passage there-through and inlaying the same between the silk threads throughout the entire area of 90 the formed fabric, so as to cause said backing threads to be held by portions of the single traverse silk threads and to be disposed so as to form with such portions of said silk threads the back of the fabric. 95

In testimony whereof I affix my signature.

PAUL H. QUICK.
